Application May 6, 1936, Serial No. 78,292

10 Claims. (Cl. 173—244)

This invention relates to the manufacture of insulated wires and cables and more particularly wires and cables insulated with a fibrous material like asbestos.

In the manufacture of insulated wires and cables in which the insulation consists in whole or in part of a fibrous material like asbestos it is customary to initially apply the fibrous material in the form of a loose layer surrounding the metallic conductor. The so-covered conductor is then customarily passed through a liquid bath of an appropriate flame-proofing compound to impregnate the layer of fibrous insulating material with the compound, and subsequently the impregnated layer of insulation is compressed and smoothed. Centrifugal devices of various types have heretofore been employed for effecting this compressing and smoothing operation. Such centrifugal devices operate in direct contact with the loosely applied and still wet layer of fibrous insulation to remove excess impregnating compound and to compact and condense the layer of insulation into a firm smooth concentric wall about the conductor. Similar centrifugal devices are also employed as smoothing burnishers on dry insulated wire for improving the appearance thereof.

The heretofore customary types of centrifugal compressing and smoothing devices have possessed certain disadvantages which may be briefly summarized as follows:

1. Lack of self-centering when used on wires of different diameters. This is especially true when the device is operated with its axis horizontal, due to the effect of gravity.
2. Lack of adjustability to control the pressure and minimum distance between the polisher shoes.
3. Location of the centrifugal mechanism in the same plane as the polishing shoes, which results in throwing off impregnating compound into bearings and other moving parts where it tends to dry or become sticky, thus rendering such parts inoperative.
4. Difficulty in cleaning the polisher shoes due to their inaccessibility.

The present invention contemplates an improved centrifugal compressing and smoothing apparatus in which the aforementioned disadvantages are overcome. Thus, in the apparatus of the invention the polisher shoes are so connected to the centrifugal mechanism that the latter transmits pressure uniformly to the polisher shoes, irrespective of the size of the insulated wire and of the operating position of the ap-

paratus. Also, in the apparatus of the invention the force of the polisher shoes and the minimum distance therebetween is susceptible of convenient predetermined control. Again, in the apparatus of the invention the centrifugal mechanism is longitudinally spaced from the zone of compression and smoothing and no difficulty is experienced by the accumulation of partially dry or sticky impregnating compounds in the operating parts. These and other advantages of the apparatus of the invention will be better understood from the following description taken in conjunction with the accompanying drawings in which

Fig. 1 is a plan view of the apparatus, 115

Fig. 2 is another view of the apparatus taken at right angles to that of Fig. 1,

Fig. 3 is a sectional elevation on the section line 3—3 of Fig. 1, and

Fig. 4 is a sectional elevation on the section line 4—4 of Fig. 1.

Referring to the drawings, the apparatus comprises a hollow rotatable spindle 5 adapted to be rotated (by means not shown) at suitable speeds. A cylindrical hub 6 is adapted to be slipped on and off the end of the spindle 5 and in operation is secured to the spindle by set screws 7. A pair of levers 8 are pivoted intermediate their ends to diametrically opposite bosses 9 on the hub 6. The levers are symmetrically positioned on opposite sides of the longitudinal axis of the spindle.

A compressing and polishing device 10 (hereinafter referred to as a polisher shoe) is pivotally mounted at one end of each of the levers 8. A fly-ball weight 11 is pivotally attached to the other yoked end of each lever 8. The inner faces of the polisher shoes 10 may be flat, cylindrical or V-shaped to provide the most efficient polishing contact. The shape will vary with the character of insulation to be compressed or polished. That portion of each lever 8 between its polisher shoe 10 and its pivot in the boss 9 is humped or outwardly bent (8') to provide a point of discharge for any impregnating compound creeping along this portion of the lever from the polisher shoe.

The weights 11 are operatively connected by a parallel linkage consisting of four yoke-ended links 12 pivoted together at their yoke ends in the shape of a diamond. Diametrically opposite pivots of the parallel linkage are pivotally connected to the weights 11, and the other diametrically opposite pivots of the linkage are pivoted to plungers 13. The plungers 13 are posi-

POLISHING APPARATUS

Beauford H. Reeves, Pine Orchard, Conn., assignor to Rockbestos Products Corporation, a corporation of Massachusetts

Application May 6, 1936, Serial No. 78,292

10 Claims. (Cl. 173—244)

This invention relates to the manufacture of insulated wires and cables and more particularly wires and cables insulated with a fibrous material like asbestos.

In the manufacture of insulated wires and cables in which the insulation consists in whole or in part of a fibrous material like asbestos it is customary to initially apply the fibrous material in the form of a loose layer surrounding the metallic conductor. The so-covered conductor is then customarily passed through a liquid bath of an appropriate flame-proofing compound to impregnate the layer of fibrous insulating material with the compound, and subsequently the impregnated layer of insulation is compressed and smoothed. Centrifugal devices of various types have heretofore been employed for effecting this compressing and smoothing operation. Such centrifugal devices operate in direct contact with the loosely applied and still wet layer of fibrous insulation to remove excess impregnating compound and to compact and condense the layer of insulation into a firm smooth concentric wall about the conductor. Similar centrifugal devices are also employed as smoothing burnishers on dry insulated wire for improving the appearance thereof.

The heretofore customary types of centrifugal compressing and smoothing devices have possessed certain disadvantages which may be briefly summarized as follows:

1. Lack of self-centering when used on wires of different diameters. This is especially true when the device is operated with its axis horizontal, due to the effect of gravity.
2. Lack of adjustability to control the pressure and minimum distance between the polisher shoes.
3. Location of the centrifugal mechanism in the same plane as the polishing shoes, which results in throwing off impregnating compound into bearings and other moving parts where it tends to dry or become sticky, thus rendering such parts inoperative.
4. Difficulty in cleaning the polisher shoes due to their inaccessibility.

The present invention contemplates an improved centrifugal compressing and smoothing apparatus in which the aforementioned disadvantages are overcome. Thus, in the apparatus of the invention the polisher shoes are so connected to the centrifugal mechanism that the latter transmits pressure uniformly to the polisher shoes, irrespective of the size of the insulated wire and of the operating position of the ap-

paratus. Also, in the apparatus of the invention the force of the polisher shoes and the minimum distance therebetween is susceptible of convenient predetermined control. Again, in the apparatus of the invention the centrifugal mechanism is longitudinally spaced from the zone of compression and smoothing and no difficulty is experienced by the accumulation of partially dry or sticky impregnating compounds in the operating parts. These and other advantages of the apparatus of the invention will be better understood from the following description taken in conjunction with the accompanying drawings in which

Fig. 1 is a plan view of the apparatus.

Fig. 2 is another view of the apparatus taken at right angles to that of Fig. 1.

Fig. 3 is a sectional elevation on the section line 3—3 of Fig. 1, and

Fig. 4 is a sectional elevation on the section line 4—4 of Fig. 1.

Referring to the drawings, the apparatus comprises a hollow rotatable spindle 5 adapted to be rotated (by means not shown) at suitable speeds. A cylindrical hub 6 is adapted to be slipped on 25 and off the end of the spindle 5 and in operation is secured to the spindle by set screws 7. A pair of levers 8 are pivoted intermediate their ends to diametrically opposite bosses 9 on the hub 6. The levers are symmetrically positioned on opposite sides of the longitudinal axis of the spindle.

A compressing and polishing device 10 (hereinafter referred to as a polisher shoe) is pivotally mounted at one end of each of the levers 35 8. A fly-ball weight 11 is pivotally attached to the other yoked end of each lever 8. The inner faces of the polisher shoes 10 may be flat, cylindrical or V-shaped to provide the most efficient polishing contact. The shape will vary with 40 the character of insulation to be compressed or polished. That portion of each lever 8 between its polisher shoe 10 and its pivot in the boss 9 is humped or outwardly bent (8') to provide a point of discharge for any impregnating compound 45 creeping along this portion of the lever from the polisher shoe.

The weights 11 are operatively connected by a parallel linkage consisting of four yoke-ended links 12 pivoted together at their yoke ends in 50 the shape of a diamond. Diametrically opposite pivots of the parallel linkage are pivotally connected to the weights 11, and the other diametrically opposite pivots of the linkage are pivoted to plungers 13. The plungers 13 are posi-55

- tioned in apertured guides 14 attached to the hub 6 and preferably integral therewith. One of the plungers 13 has a threaded aperture in the outer end thereof, and a headed screw 15 is threaded in the aperture. The head of the screw is larger than the aperture of the guide 14 and when the head of the screw seats against the outer end of the guide 14 the plunger is restrained from further inward movement.
- 10 In the operation of the apparatus of the invention, the hub 6 is mounted on and secured to the revolving spindle 5 of the compressing and polishing machine. The spindle may be in a horizontal or vertical position depending upon the type of 15 the machine. The spindle is tubular to permit the axial passage therethrough of the wire 16 to be compressed and polished. The polisher shoes 10 are so supported that they can swing in the axial plane of the wire and thus insure uniformity 20 of contact and pressure throughout their length. The spindle 5 is rotated at a suitable speed to bring the polishing shoes into operation through the effect of centrifugal force on the weights 11. Appropriate means are provided to pull the 25 insulated wire longitudinally and axially through the tubular spindle and between the polisher shoes at the proper linear speed in relation to the revolving speed of the spindle and polisher shoes to get the desired finish.
- 30 Polisher shoes of different sizes and fly-balls of varying weights to suit wires of different types may be used and are easily interchanged. The complete mechanism can be removed as a unit and replaced by another. All parts are assembled 35 in operating relation on the central hub 6 and are readily accessible for repair, renewal and cleaning.
- The advantages of the improved compressing and smoothing apparatus of the invention may be briefly summarized as follows:
- 40 1. The parallel linkage connecting the levers 8 (through the weights 11) and the plungers 13 necessitates equal radial movement of the weights (and polisher shoes) regardless of the position in 45 which the apparatus operates or of the size of the wire being processed.
2. The closing of the polisher shoes to apply pressure to the insulation of the wire being processed is controlled by the adjusting screw 15 in 50 one of the plungers 13 by the fact that the head of the screw is larger than the hole in the plunger guide 14 so that when the head of the screw seats against the end of the guide, the plunger is restrained from further inward movement. This 55 prevents (through the connection of this plunger with the parallel linkage) the weights 11 from further outward movement, and, therefore, limits the minimum distance between the polisher shoes.
3. By the bell-crank construction of the levers 60 8, the entire centrifugal operating mechanism is removed from the zone of actual polishing and applying impregnating compound, and no difficulty is experienced due to accumulation of partially dry or sticky compound in the operating 65 parts.
4. The humped shape of the levers 8 between the polisher shoes 10 and the hub 6 insures that any impregnating compound which might creep up the levers from the polishing zone will be 70 thrown off the levers by centrifugal force before it can reach the bearings or pivots of the levers in the bosses 9 of the hub 6.
5. The pressure of the polisher shoes increases 75 gradually from zero to a maximum as the machine is started up and decreases correspondingly

as the machine is stopped. This prevents twisting of the insulated wire and consequent objectionable disturbance of the insulation.

6. Cleaning the polisher shoes is very easy since they are accessible from all sides and are easily removed if necessary.

I claim:

1. In an apparatus for compressing and smoothing insulation about a metallic conductor, the combination with a rotatable spindle of a hub adapted to be secured to said spindle, a pair of levers pivoted intermediate their ends to said hub and symmetrically positioned on opposite sides of the longitudinal axis of said spindle, each of said levers carrying a compressing device at one end thereof and a weight at the other end thereof, and parallel linkage operatively connecting said weights.

2. In an apparatus for compressing and smoothing insulation about a metallic conductor, the combination with a cooperating pair of compressing devices of a pair of centrifugally responsive weights operatively connected to said compressing devices and longitudinally spaced therefrom, and parallel linkage comprising a plurality of pivoted links operatively connecting said weights.

3. In an apparatus for compressing and smoothing insulation about a metallic conductor, a cooperating pair of compressing devices, a pair of centrifugally responsive weights operatively connected to said compressing devices and longitudinally spaced therefrom, and parallel linkage comprising a plurality of interconnected links operatively connecting said weights whereby pressure due to the centrifugal action of said weights is transmitted uniformly to each compressing device.

4. In an apparatus of the character described for processing insulation about a metallic conductor, the combination with a rotatable spindle of a pair of cooperating compressing devices symmetrically positioned on opposite sides of the longitudinal axis of said spindle, a pair of centrifugally responsive weights symmetrically positioned on opposite sides of the longitudinal axis of said spindle and longitudinally spaced from said compressing devices, means operatively connecting said compressing devices to said weights and to said spindle, and linkage means operatively connecting said weights to one another whereby pressure due to the centrifugal action of said weights is transmitted uniformly to each compressing device.

5. In an apparatus of the character described for processing insulation about a metallic conductor, the combination with a cooperating pair of compressing devices of a pair of centrifugally responsive weights operatively connected to said compressing devices and longitudinally spaced therefrom, parallel linkage operatively connecting said weights, and means comprising a plurality of pivoted members cooperating with said linkage for limiting outward movement of said weights due to centrifugal action.

6. In an apparatus for compressing and smoothing insulation about a metallic conductor, the combination with a rotatable spindle of a hub adapted to be secured to said spindle, a pair of levers pivoted intermediate their ends to said hub and symmetrically positioned on opposite sides of the longitudinal axis of said spindle, a compressing device attached at one end of each lever, the portion of said levers between said hub and said compressing devices being outward-

ly humped to provide a centrifugal discharge point for liquid removed from the insulation, and a centrifugal mechanism operatively connected to the other ends of said levers.

- 5 7. In an apparatus for compressing and smoothing insulation about a metallic conductor, the combination with a rotatable spindle of a hub adapted to be secured to said spindle, a pair of levers symmetrically positioned on opposite sides of the longitudinal axis of said spindle, each of said levers being pivoted intermediate its ends to said hub, a compressing device operatively attached to one end of each lever, said compressing devices being symmetrically positioned on opposite sides of the longitudinal axis of said spindle and longitudinally spaced from said hub, a weight carried by the other end of each lever, and parallel linkage operatively connecting said weights.
- 10 8. In an apparatus for compressing and smoothing insulation about a metallic conductor, the combination with a rotatable hollow spindle of a hub adapted to be secured to said spindle, a pair of levers symmetrically positioned on opposite sides of the longitudinal axis of said spindle, each of said levers being pivoted intermediate its ends to said hub, a compressing device pivoted to one end of each lever, said compressing devices being symmetrically positioned on opposite sides of the longitudinal axis of said spindle and longitudinally spaced from said hub, a weight carried by the other end of each lever, parallel linkage surrounding said spindle and

having one pair of its diametrically opposite pivots attached to said weights respectively, a plunger attached to each of the other diametrically opposite pivots of said linkage, a guide for each of said plungers attached to said hub, 5 and means cooperating with one of said plungers for limiting its inward movement in response to the force imparted thereto by the centrifugal action of said weights.

9. In an apparatus of the character described 10 for processing insulation about a metallic conductor, the combination with a rotatable spindle of a plurality of compressing devices, a centrifugally actuated weight connected to each compressing device, a linkage interconnecting 15 said weights, and means operatively connected to said linkage for limiting the outward movement of said weights.

10. In an apparatus for compressing and smoothing insulation about a metallic conductor, 20 the combination with a rotatable spindle of a hub adapted to be secured to said spindle, a pair of levers pivoted intermediate their ends to said hub, each of said levers having a compressing device attached to one end thereof and a weight 25 on the other end thereof, and a parallelogram linkage connecting the weights, said levers extending in the longitudinal direction of the apparatus, thereby supporting the weights and compressing devices in longitudinally spaced positions. 30
